UNITED STATES PATENT OFFICE.

THOMAS E. CHANDLER, OF INDIANAPOLIS, INDIANA.

DESIGN FOR MULEY-SAW FRAME.

Specification forming part of Design No. 7,905, dated December 1, 1874; application filed November 19, 1874.
[Term of Patent 7 years.]

To all whom it may concern:

Be it known that I, THOMAS E. CHANDLER, of Indianapolis, county of Marion, State of Indiana, have produced a new and ornamental Design for a Muley-Saw Frame, which is fully represented in the accompanying drawings forming part of this specification, to which reference is made.

The frame is of cast-iron, with a projecting rib about its outer edge and flanges A at the top, to which the upper slides for the saw are bolted. The flanges B serve the same purpose for the lower slides, and the broad flanges C give it a firm base to stand upon, while the small orifices in them serve for the passage of the bolts by which the frame is secured to the bed-plate. The web of the frame is also

pierced with several apertures, each of them surrounded by a projecting molding. These apertures serve to reduce the weight and form guards for parts of the machinery, as well as add an appearance of lightness and elegance to the frame.

Having thus described my invention, I claim the following:

The design for a muley-saw frame, as herein shown and described.

In testimony that I claim the foregoing I hereunto affix my signature in the presence of two witnesses.

THOMAS E. CHANDLER.

Witnesses:

M. P. HARWOOD,
L. TOWLE.
